VECTOR RESOLVING INTEGRATOR

Willard E. Oliphant, New York, N. Y.

Application April 25, 1942, Serial No. 446,431

5 Claims. (Cl. 235—61)

The invention relates to mechanical devices for the analysis of vectors.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a longitudinal central section through a device embodying the invention;

Fig. 2 is a section taken on line 2—2 of Fig. 1;

Fig. 3 is a fragmentary view, partly in section of an electrical contact finger;

Fig. 4 is a section taken on line 4—4 of Fig. 1;

Fig. 5 is an end elevation of the device shown in Fig. 1;

Fig. 6 is a section taken on line 6—6 of Fig. 1;

Fig. 7 is a diagrammatic side view of a vehicle showing the approximate position of the invention in relation thereto;

Fig. 8 is an electrical diagram of the circuits for operating the device;

Fig. 9 is a longitudinal central section through the recording portion of the invention;

Fig. 10 is a section taken on line 10—10 of Fig. 9;

Figs. 11 and 12 are fragmentary sections taken on lines 11—11 and 12—12 of Fig. 10; and

Fig. 13 is a plan view of the recording mechanism.

The invention is primarily directed to a new and useful mechanism for making continuous mechanical analyses of vector quantities into their components. The invention provides mechanism whereby a vector of any angle and sense may be analyzed into its components, having given its length and direction. Moreover the invention provides mechanism for continuously providing mechanical solutions of such vector analyses while the length and direction of the vector changes or varies. Stated another way, the invention provides mechanical means for continuously solving right triangles where the length of the hypotenuse and either acute angle is known, such solution being continuous regard-

less of the variations in the given quantities and/or the quadrants in which the triangle may be considered to be located. With the foregoing basic mechanism the invention provides means for applying the solutions of said triangles or vector components to the performance of mechanical work. For example, the present preferred embodiment of the invention utilizes the solution of the basic geometric problem for movement in two axial directions on a map. By suitable indicating means cooperating with such map, it is thereby possible to inscribe a continuous record of the path of a vehicle with relation to the map and continuously therewith to maintain an indication of the position of the vehicle on the map.

Other applications of the invention include its use in electric meter installations where similar vector analysis problems arise; the tracking of the movements of a ship with relation to a chart; use in aircraft, in connection with other instruments such as a ground speed indicator, to locate the plane with relation to the ground; various uses in artillery fire-control instruments where the continuous solution of right triangles is a basic problem; control of other triangulation instruments such as bomb sights, etc. It will be understood that the invention is one of general application and the foregoing suggested uses are illustrative, but not limiting thereof. The mechanism provided by the invention is highly accurate, while also providing means sufficiently rugged and powerful that the mechanical movements produced by the device may be transmitted directly to work-performing instruments.

In the present preferred embodiment the invention is shown as applied to the continuous recording and indicating of the position of a motor vehicle on land whereby continuous orientation of the vehicle with respect to a map of the terrain is provided. The invention provides a very rugged and practical mechanism for solving the geometrical problem and recording same on a map as stated, whereby the motions of travel of the vehicle and directional movements thereof (imparted by steering gear or other means) are utilized in the instrument to carry out the operational solutions required.

Referring to the drawings, and more particularly to Figs. 1 to 8, there is shown a combined mechanical and electrical device adapted for actuation by a moving vehicle, such as an automobile, and in turn adapted to actuate a mechanism for recording as on a map and at a reduced scale, the path traveled by the vehicle. As

embodied, a generally cylindrical casing 10 is provided which for constructional purposes may be formed in two parts and joined by aligned flanges 11, 12 and screws 13. The ends of casing 10 are closed by cover plates 14, 15 which are also properly aligned with the casing 10 as by shouldered portions 16, 17 and secured to the casing by screws 18, 19. Within the casing 10 and its cover plates 14, 15, there are mounted and journaled the various mechanical and electrical parts to accomplish the objects of the invention.

A main shaft 20, extending through the center of casing 10 and journaled at each end in the cover plates 14, 15, projects beyond the cover plate 14 a sufficient distance to provide a driving connection with one end of a flexible shaft 21, the other end of which may be driven from any desired rotating portion of a vehicle which is proportionate to its actual speed and lineal movement. As shown (Fig. 7) flexible shaft 21 may be driven by the conventional speedometer gears 22 of an automotive vehicle M having the usual engine 23, transmission 24, propeller shaft 25 and rear driving wheels 26.

The main shaft 20, the rotation of which is directly proportional to the speed and distance traveled by the vehicle, has secured thereon, near the end journaled in cover plate 15, a sun gear 30 which meshes with and drives four pinions 31F, 31L, 31B and 31R. These pinions are arranged about the sun gear 30 at the four quarter points and mounted for free rotation upon hollow hubs 35 which project inwardly from the cover plate 15.

Mechanism associated with each of the four pinions 31F, L, B and R, is provided whereby at intervals determined by the vehicle motion, that is its travel in a straight or curved course, a portion of the motion of sun gear 30 is transmitted to one or more of certain actuator spindles. As embodied, there are provided four actuator spindles 36F, 36L, 36B and 36R, one end of each spindle being journaled in one of the hubs 35 and projecting out of the cover plate 15, to provide a driving connection to a recording device to be described later. The inner end of each spindle is journaled in a web 37 extending inwardly from the wall of casing 10.

Each of the spindles 36F, L, B and R, is adapted for rotation at certain intervals and for a certain number of revolutions by temporary connection to its associated pinion 31F, L, B or R.

Since all four spindles are alike, a description of one will suffice. The central portion 38, of the spindle 36F, may be squared to receive the axially slidable clutch member 40, the mass of which forms the core of a double coil solenoid. The end face of clutch member 40, adjacent the pinion 31F, may be provided with teeth 41, which preferably are comparatively small and numerous to reduce lost motion, during engagement, to a minimum. Teeth 42 on the hub of pinion 31F correspond to and cooperate with teeth 41 to form a complete clutch unit.

Surrounding the core clutch member 40, but spaced therefrom to permit movement of the core, are two actuating coils 43e and 43d which may be wound upon a spool 44, and clamped against a ledge member 45, projecting from the casing wall, by bolts 46 and end plate 47. The core member 40, and coils 43e and 43d, thus form a double acting solenoid 50F, which serves either to engage or disengage the clutch teeth 41, 42, as electrical current is passed through

either coil 43e or coil 43d. A similar double acting solenoid 50L, 50B and 50R is provided in operative relation to each of the spindles 36L, 36B and 36R. As will be clear from the drawings, when the coil 43e is energized, the core clutch member 40 will be moved to the right (Fig. 1) to engage the clutch teeth 41, 42, while energization of coil 43d will serve to disengage the clutch teeth. Pinion 31F (as well as pinions 31L, 31B, 31R) is rotating at all times during vehicle travel, but transmits its motion to its associated spindle 36F only during the time coil 43e is energized, and clutch teeth 41, 42 are engaged.

Means are provided for energizing the solenoid coils 43e, 43d at desired intervals in relation to the rotation of main shaft 20. As embodied, there is secured to shaft 20, a commutator drum 51 upon the periphery of which are three contact bands 52, 53, 54, electrically separated from each other by narrow bands of insulation 55, 56. The two end contact bands 52, 54 are electrically interconnected by a wire 57, or other means. The body of drum 51 may be formed of insulating material or otherwise insulated from shaft 20. A spring contact finger 58 is fixed on an insulated block 59, which is secured on a slide bar 60 in fixed relation to drum 51, so that said finger 58 always is in contact with drum band 54. An electrical connection is provided from contact finger 58 to one end of each of the coils 43e in solenoids 50F, L, B and R (not shown in Fig. 1, but diagrammatically indicated in Fig. 8, and to be described later).

A second spring contact finger 61 is secured on insulated block 59 in such a position as always to maintain contact with drum band 53, and is electrically connected to one end of each of the coils 43d of the four solenoids 50F, L, B and R.

There are four of the slide bars 60 provided and positioned at the four quarter points about the drum 51 but only one set of contact fingers 58 and 61 is necessary, and it is arbitrarily mounted on the slide bar 60, which is adjacent solenoid 50F. Each slide bar 60 has slidably mounted thereon, a slide block 62, which carries, but is insulated from, a spring contact roller. The four contact rollers, designated as 63F, L, B and R, are electrically connected by means of conductors (not shown in Fig. 1) to both of the coils 43e and 43d of the solenoids 50F, L, B and R, respectively.

Means are provided for positioning each of the contact roller 63F, L, B and R on the drum 51, so that, as the drum rotates, either one contact roller or two adjacent rollers will, during one drum revolution, pass over a wedge-shaped portion x of the middle drum contact band 53, while the remaining two or three rollers only make contact with the inner band 52. As embodied, each slide block 62 is provided with a cam roller 66, and a tension spring 67, which is anchored at one end on block 62, and at the other end on casing web 37, said spring serving to maintain cam roller 66 in contact with a cam 70, which is journaled upon main shaft 20, and held in axial position thereon by collars 71.

Cam 70 does not partake of the motion of main shaft 20, but is controlled in its angular position by the direction in which the vehicle may be traveling, and shifted from this position as the vehicle changes its course and to the same degree. Thus, if the vehicle turns from due north to a northeast course, it has moved through an

arc of 45°, and the cam is likewise turned 45° and in a corresponding direction.

The cam 78 has its cam surface arranged as follows: a low level surface α is provided and occupies an arc of 180° and this surface α is such as to maintain any of the contact rollers 83F, L, B or R at a point on the inner drum band 82 just beyond the point of the wedge portion χ of the middle band 83. Thus, as the drum 81 rotates, any contact roller positioned by cam surface α will never make contact with the middle band 83. The remaining 180° arc of cam 78 comprises a rise and fall which constitutes a sine curve b . The crest of sine curve b is such as to move any contact roller, for example, 83F, to a point on the drum 81 whereby, as the drum rotates, the roller will make contact with the wedge portion χ of the middle drum band 83 at the point where the circumferential extent of the wedge occupies a 90° arc of the surface of drum 81. Thus if the crest of sine curve b is aligned with a contact roller, for example 83F, that roller traces a path across wedge χ at its maximum functional width, and during the time of this contact with wedge χ , the coil 82e of the solenoid 80F is energized and its associated clutch engaged, thereby transmitting the motion of main shaft 28 to spindle 36F for the duration of this contact. Therefore, under the condition just described, each revolution of main shaft 28 and drum 81 will, during one quarter of this revolution, rotate spindle 36F, and this rotation represents a direct proportion of the distance traveled by the vehicle in a specific direction. Continued rotation of shaft 28 by vehicle movement and with no change in the position of cam 78 will thus produce a proportional rotation of spindle 36F which may be utilized to operate an associated mechanism for indicating and recording on a reduced scale the vehicle travel in distance and compass direction.

The relation between sine curve b of cam 78 and wedge portion χ of drum band 83 is as follows: The amplitude of sine curve b is equal to the altitude of an isosceles triangle formed by wedge portion χ in which the two sides of the triangle are the sides of the wedge χ and the base is a circumferential line representing a 90° arc on drum 81. (See Fig. 8.) The distance between the ends of the sine curve b is equal to twice the base length of the said triangle of an arc of 180° on the cam circumference.

If the cam 78 is, as in the form of the invention illustrated, utilized to represent the compass direction of vehicle travel, the purpose of the relationship between cam 78 and the contact wedge χ of drum 81 is to produce in the spindles 36F, L, B and R such number of rotations as will represent, when recorded, the actual distance traveled by the vehicle in any direction. Thus, the four spindles may represent respectively, in relation to a selected course of travel (a trip in which the destination is due north of the starting point), the forward or north travel (spindle 36F), travel 90° left of the course or west (spindle 36L), travel at 90° right or east (spindle 36R) and travel directly away from the destination or south (spindle 36B). If, however, the travel is in a direction such as northeast, two adjacent spindles, such as 36F and 36R, are actuated and the duration of this actuation will be such as can be combined in a recorded resultant which will be equivalent to the same distance traveled either due north or east. Similar action takes place for other directions. In other words, if the ve-

hicle travels due north for ten miles, contact roller 83F is aligned with the crest of sine curve b and will pass over the wedge χ of drum 81 at the maximum functional width thereof and therefore cause spindle 36F to rotate the equivalent of ten miles. This may be recorded by a stationary stylus upon a map moved by said spindle. If, however, the vehicle is turned to the right 45° and pursues a north east course for ten miles this action causes the cam 78 to rotate 45° (by means to be described later). The crest of sine curve b is thus brought midway between contact roller 83F and contact roller 83R and their position on drum 81, as determined by their cam rollers 86 upon the cam 78, is such that as the drum rotates they each pass over the wedge χ along a line between the wedge point and the maximum functional wedge width (the base of the triangle previously referred to). The proportion of the length of this line of contact to the maximum wedge width is as the sine of the angle through which the cam 78 was turned, i. e., 45°, is to unity. Consequently, as the northeast course is pursued, the spindle 36F is rotated, during the revolution of main shaft 28, an amount equivalent to the "northing" made on the northeast course and spindle 36R is rotated an amount equivalent to the "easting" made on that course. The motion of the two spindles when combined by an indicating or recording device will thus produce a resultant line on a map which will represent a ten mile run on a northeast course. As illustrated, and to be described later, the spindle 36F may move a map the distance equivalent to the "northing" component of vehicle travel and spindle 36R may move a stylus a distance equivalent to the "easting" component but at a right angle to the map movement. The line thus produced on the map is the resultant of the two spindle rotations and represents a northeast course pursued for ten miles.

Similar action takes place for other positions of cam 78 wherein, for any course which deviates from the four quarter points of a selected course, the sine curve b causes the appropriate two adjacent contact rollers to assume positions on drum 81 whereby their paths across wedge portion χ represents the sine and the cosine of the angle of deviation from the true-course direction of the destination. The two remaining contact rollers, of course, are positioned by the low level α of cam 78 and hence do not contact wedge portion χ of drum band 83 thereby serving only to maintain the respective clutches of their associated spindles in disengaged position.

Referring now to the means for orienting the cam 78 in response to a change in course of a vehicle, and to a like degree, there is secured to the left hand face (Fig. 1) of the cam 78 a disc 76, the periphery of which is provided with gear teeth 76 that mesh with a pinion 77 journaled in a ledge 78 which projects inwardly from the wall of casing 10. The stub shaft 79 of pinion 77 has fixed thereto a clutch member 81 adapted to be engaged by a corresponding clutch member 81 which also forms the movable core of a double coil solenoid 82 having coils 82d and 82e that are wound upon a spool 83. Solenoid 82 is fixed to a bracket 84 projecting inwardly from the wall of casing 10, a clamping plate 85 and bolts 85' serving for this purpose. The core clutch member 81 is of such length in relation to the two solenoid coils 82d and 82e that when coil 82e is energized the clutch member 81 is moved to en-

gage the pinion clutch member 80, but if coil 82d is energized the clutch is disengaged.

Clutch member 81 is slidably mounted upon the squared end 86 of a shaft 87 which is journaled in the bracket 84 and the end plate 14. Midway between these two journals there is provided a two-way gear drive and double clutch mechanism comprising a pair of bevel gears 90, 91, mounted upon shaft 87 for free rotation thereon and a sliding clutch member 92 splined to shaft 87 and adapted, upon appropriate movement, to engage either of the corresponding clutch members 93, 94 formed respectively upon the opposing faces of bevel gears 90, 91 and thereby rotate shaft 87 in a direction corresponding to whichever bevel gear is connected thereto.

Slidable clutch member 92 may be actuated by a lever 95, pivoted at 96 and extending to the outside of the casing 10 through an aperture 87 therein. The end 98 of lever 95 is pivotally connected to an actuator bar 100, each end of which forms a movable core within solenoids 101R and 101L. Between the facing ends of solenoids 101R and 101L, and surrounding the bar 100, are two centering springs 102, 103, which act upon the lever 95 so that sliding clutch member 92 is normally held out of engagement with either clutch member 93, 94. Thus, when either one of the solenoids 101R and 101L is energized the shaft 87 will be placed in driving connection with the corresponding bevel gear.

The bevel gears 90, 91 are driven in opposite directions by meshing with a common bevel gear 104 at diametrically opposite points. Gear 104 is driven from the main shaft 20 through a gear 105, fixed thereon, and gear attached on a stub shaft 107 which also has fixed thereon the gear 104. Stub shaft 107 is journaled in a split bearing 108 formed as part of bracket 84.

Means are provided for automatically energizing either solenoid 101R or 101L as the vehicle turns to the right or left of the major axis of the selected course and thereby cause rotation of shaft 87 in either corresponding direction. As embodied, a cam shaft 110 is journaled within the casing 10 and has fixed upon its inner end a multiple cam drum 112. Shaft 110 is also journaled in the cover plate 14 and projects a short distance out therefrom to provide a point of attachment for one end of a flexible shaft 113 the other end of which may be connected to some portion of the steering mechanism of the vehicle which will rotate the shaft 113 an amount directly proportional to the angular displacement of the wheels during steering. (See Fig. 7.) One form of this connection is indicated in Fig. 7 and comprises a spur gear 114 fixed upon the pitman arm shaft 115 of the vehicle steering mechanism and a meshing pinion 116 fixed upon the end of flexible shaft 113. It is to be understood that other driving connections between the steering mechanism and the cam shaft 110 may be employed within the scope of the invention.

A pair of so-called micro-switches 117R and 117L are mounted upon a ledge 118 forming part of the casing and are placed one on each side of cam drum 112 so as to be actuated thereby. Micro-switch 117R is electrically connected to solenoid 101R and micro-switch 117L is connected to solenoid 101L (shown in Fig. 8). Each switch is normally in open position when the vehicle is moving in a straight course, but when the vehicle turns right a cam surface 120R on drum 112 immediately actuates the spring finger of switch 117R and closes the circuit to solenoid

101R, which, in turn, causes shaft 87 to rotate in a direction corresponding to a right hand turn. A similar but oppositely-disposed cam surface 120L on drum 112 actuates the switch 117L and thereby energizes solenoid 101L in response to a left turn of the vehicle, the shaft 87 then being rotated in the opposite direction to that just described.

Reference is now made to the means for orienting the cam 70 through the same angle that the vehicle traverses in following a curved course and thereby positioning the various contact rollers 63 at their proper points along drum 51 to represent this course. The mechanism to accomplish this comprises combined electrical-mechanical devices which insure that the cam 70 is always turned through the same angle as that through which the vehicle turns regardless of the length of the arc which subtends this angle, or, expressed differently, the angle of vehicle turn is always transmitted to cam 70, regardless of whether that angle is traversed as a long gradual curve having a great radius, or a short sharp curve with a minimum radius. Thus, if the vehicle traverses a curve of 50 foot radius for a distance of 78.54 feet, it has turned through an arc of 90°, and it also turns through a 90° arc if it travels 314.16 feet along a curve having a radius of 200 feet. In both cases the cam 70 will be turned 90°.

The mechanism as embodied comprises a commutator drum 125 fixed on main shaft 20 and similar to drum 51. Three contact bands 126, 127 and 128 are secured to the periphery of the drum and electrically insulated from each other by narrow strips 129, 130. The middle band 127 is provided with a wedge portion y the point of which projects into a complementary notch in band 126. The band 126 is electrically connected to band 128 by a wire 131. Supported upon the ledge 118 and adjacent to the drum 125 is a guide bar 132 near the free end of which is fixed a block of insulating material 133. Spring contact fingers 134, 135 are fixed on block 133. Finger 134 makes contact with drum band 127 and is connected to the coil 82d of solenoid 82. Finger 135 makes contact with drum band 128 and is connected to the coil 82e of solenoid 82.

Slidably mounted upon the guide bar 132 is a block 136 having a cam roller 137 upon its outer face which is acted upon by a cam 138 formed upon the end of cam drum 112. A tension spring 139 between the slide block 136 and the base of guide bar 132 serves to insure contact of cam roller 137 and cam 138 at all times. A spring finger 140 is secured to the inner face of slide block 136 but is insulated therefrom, and carries at its extended end a contact roller 141 adapted to roll upon commutator drum 125. Thus, as the cam 138 is oscillated, the slide block 136 assumes various positions on guide bar 132, and contact roller 141 contacts corresponding points on drum 125. The contact roller 141 is electrically connected to both the coils 82d and 82e of solenoid 82.

The contour of cam 138 is correlated to the vehicle steering means so that the amount of rise from the low point to either of two high points represents the angular traverse of the steering wheels from 0 degrees (straight course) to the maximum angle to which the wheels can be set (sharpest curved course). The degree of rotation of cam 138 to bring either of its high points to a position beneath cam roller 137 is directly proportional to the degree of rotation of the steering wheels about their king pins. As illustrated,

the cam 138 is shown as requiring a 90° rotation in either direction from that assumed when the vehicle is on a straight course to bring either of the two high points beneath the cam roller 137. The point *m* on cam 138 represents a straight course, the rise *n* represents a right turn of increasing sharpness with point *r* representing the shortest radius turn of which the vehicle is capable and the rise *s* represents a left turn with point *t* representing the sharpest possible left turn.

The relation between cam 138 and the wedge portion *y* of drum band 127 is as follows: The distance through which the cam rise moves contact roller 141 along drum 125 equals the distance from a point just off the apex of the wedge *y* to a circumferential line *w* on drum 125. This line *w* crosses the two sides of wedge *y* at points equi-distant from the wedge apex. The portion of the line *w* lying upon the wedge *y* is the maximum functional width of the wedge *y*, and its length in relation to the various gear ratios in the drive system between the vehicle wheels and the cam 78, is such that as the vehicle makes a complete circle having its shortest possible radius the cam 78 is likewise given one complete revolution due to the passage of contact roller 141 over the wedge *y* at the line *w*.

During the time contact roller 141 is on the wedge portion *y*, the coil 82e of solenoid 82 is energized, the clutch 88, 81 is engaged and the motion of shaft 81 is transmitted through gears 17, 76 to cam 78. As the roller 141 leaves wedge portion *y* and contacts drum band 126, the coil 82d is energized and clutch 88, 81 is disengaged until the next revolution of drum 126.

Since the number of revolutions of drum 125 is directly proportional to the distance traveled by the vehicle and a specific portion of each revolution is transmitted to the cam 78 it is obvious that the length of the arc of vehicle travel is convertible into an arcuate movement of cam 78 through the same angle as that subtended by the said arc.

If the portion of each revolution of drum 125 which is transmitted to cam 78 is changed in the same ratio that the arc length of travel changes when turns of various radii are made through the same turn-angle, the arcuate movement of the cam 78 will be equivalent to the angle of that arc. Thus, for example, if a vehicle is turned at its minimum radius, say 25 feet, the length of the arc for a 90 degree turn is 39.27 feet. Assuming that 20% of each revolution of drum 125 is transmitted to cam 78 by passage of contact roller 141 over the line of maximum wedge width and that this percentage is such that cam 78 is thereby rotated 90 degrees, it will be clear that if the roller 141 passes over a line half way between the maximum wedge width and the wedge apex the clutch 88, 81 will be in engagement only half as long during each revolution of the main shaft 20 and only 10% ($\frac{1}{2}$ of previous amount) of the main shaft rotation is transmitted to cam 78. This latter position of roller 141 occurs when cam 138 has been turned 45° towards the low point *m* by action of the vehicle steering mechanism and indicates that the vehicle is traveling a course having a radius twice as long as its minimum radius, or 50 feet. To complete a 90° turn at this radius, the vehicle must travel an arc of 78.54 feet. But, while only 10% of each revolution of the main shaft 20 is transmitted to cam 78, the shaft rotates twice as many times on the arc of 78.54 feet as it did for the 39.27 foot

arc, and therefore, the same amount of total arcuate motion is given to cam 78 and it is turned through a 90° arc. Similar action takes place for all other vehicle turns from its minimum turning radius to its maximum. When the vehicle is no longer turning but is on a straight course, the cam roller 137 is at the low point *m* on cam 138 and contact roller 141 just misses making contact with wedge portion *y* on drum 125. In this condition solenoid coil 82e is never energized and none of the motion of main shaft 20 is transmitted to cam 78 which then remains at whichever point it reached at the moment the vehicle regained a straight course after a turn from a previous course in a different direction.

The position of cam 78 may be utilized to provide visible indication of the compass direction in which the vehicle may be traveling. As embodied, the enlarged central portion of casing 10 may be provided with a window 145 at a convenient place. A point of reference such as a marker 146, secured to the outside of casing 10 and projecting a short distance into the window area, serves, in conjunction with a compass card disc 147, to enable an operator to determine the direction of travel. The compass card 147 may be frictionally held in a recess formed between the cam 78 and gear disc 75 and thereby to move with the cam 78. The compass points inscribed upon compass card 147 are so arranged as to be visible through window 145 and to present under marker 146 the correct compass point indicating the direction of travel. In the mechanism illustrated, for example, the compass points are arranged in a counter-clockwise direction around the card 147 in the order north, east, south and west. Thus, if the vehicle is traveling north and turns east, the cam 78 and card 147 are turned clockwise (as viewed from the right in Fig. 1) and the east point will appear beneath the marker 146.

Since it is necessary that the mechanism can be set to accommodate itself to a trip having its major axis in any selected direction, means have been provided to accomplish this, when the vehicle is at rest, in an easy and convenient manner. As embodied, an inturned flange 148 is provided on the compass card disc 147 and a manually operable spring retracted detent 149 mounted in the wall of casing 10 at a point adjacent flange 148. Detent 149, when pressed and held inwardly against flange 148 prevents movement of disc 147, but due to the frictional mounting of disc 147 on cam 78 movement of the latter is still possible. A pointer 150 is secured to the cam 78 in accurate alignment with the crest of sine curve *b* and extends outwardly so as to be visible, on occasion, through the window 145.

Manual rotation of cam 78 to set it in a position to correspond to the compass direction of the vehicle at the start of a trip is accomplished by a bevel pinion 151 adapted to mesh with a bevel gear 152 formed on the face of gear disc 75. The pinion 151 is fixed on the end of a shaft 153, journaled in a boss 154 formed as part of casing 10, and is normally held out of engagement with gear 152 by a spring 155 which is seated between the casing 10 and the hub of a knob 156 fixed upon the external end of shaft 153. Thus if knob 156 is pressed inwardly and rotated, bevel gears 151 and 152 mesh and cam 78 is rotated.

The sequence of steps in setting the device for a selected trip is as follows: Assume a vehicle at rest, headed due east and ready for a trip having a north-south major axis in which the destina-

tion is substantially north of the starting point. First: Press in and turn knob 156 until the "north" point on compass card 147 is aligned with window marker 146. Second: Press in detent 149 until it strikes flange 148. While thus preventing further movement of the compass card 147, again turn knob 156 until the cam pointer 150 appears in the window and is aligned with the marker 146 and the "north" point on the compass card. The device is now set for registering the vehicle movements on a north trip. It remains to make one more setting, which will correlate the device with the actual position (headed east) of the vehicle as it is ready to start the trip. Releasing the detent 149, the knob 156 is again turned until the "east" point of the compass card is aligned with the marker 146. Upon release of knob 156 the device is ready to register correctly, upon the various spindles 36, all of the movements of the vehicle, the initial movement being east and registered upon the spindle 36R. As the vehicle continues and the operator swings through a left turn to a true north course, the cam 70 is correspondingly turned and to the same degree, moving the crest of sine curve b from alignment with spindle 36R to successive positions between spindles 36R and 36F and finally in alignment with spindle 36F as the vehicle straightens out upon its north course. It may be noted here that the drawings illustrate the positions of the various parts of the device to correspond to the above assumed example after the vehicle has straightened out upon its north course.

Referring now to the circuit diagram illustrated in Fig. 8, it will be noted that the contact drum 51, cam 70, contact drum 125 and cam 138 are shown with their cylindrical surface developed into planes and the positions of the various members corresponding to those assumed when the vehicle is traveling on a straight course and due north. A source of electrical energy is indicated at 160 and may be the usual storage battery of the vehicle. A main switch 161 may also be provided at a point in the circuit to render the device inoperative when desired. The path of the current to double-coil solenoids 50F, L, B and R is as follows: from battery 160 the current passes along conductor 162, line 163, and through coils 43d of each of the solenoids 50R, L and B, which are energized and maintain their respective clutches on their associated spindles in the disengaged position. From the said coils the current passes along lines 164, 165, 166 to the contact points 63R, L and B, then through drum band 52, wire 57, drum band 54, contact 58 and line 167 to battery. In the case of solenoid 50F, the current passes from battery along line 162 to contact finger 61, then through drum band 53, contact point 63F, wire 168, coil 43e of solenoid 50F, line 169 and line 167 to battery. The clutch associated with solenoid 50F is thereby engaged and spindle 36F will rotate as long as contact point 63F remains on wedge portion x of drum band 53.

In the case of contact drum 125, current passes from battery 160, along line 162, line 170, through coil 82d of solenoid 82, line 170', contact point 141, drum band 126, wire 131, drum band 128, contact finger 135, line 171 and line 167 to battery. If, however, the cam 138 had raised the contact point (roller) 141 so as to pass over wedge portion y of drum band 127, the current then would pass from battery, along line 162, line 172, contact finger 134, drum band 127, contact point 141, line 170', solenoid coil 82e, line 173 and line 167 to battery.

The course of current to actuate solenoid 101R when a right hand turn is made (as from north to east) is as follows: From the battery 160, current passes along line 162, line 174, 175, solenoid coil 101R, line 176, micro-switch 117R (when cam 120R closes same), line 177 and line 167 back to battery. In a left hand turn the current passes from battery 160 along line 162, line 174, 178, solenoid coil 101L, line 179, micro-switch 117L, line 180, line 177 and line 167 back to battery.

Reference is now made to the means for recording the motions of the four spindles 36F, L, B and R, so as to produce a traced line upon a map which will indicate at a reduced scale the course of travel of a vehicle. (See Figs. 9 to 13.) A bracket 200 is provided in which the various shafts are journaled and the map supported. Bracket 200 is adapted to be secured to the casting cover plate 15 of the map actuating device as by end flange 201 and screws 202. Journaled in appropriate bearings in bracket 200 are four spindle shafts 205 F, L, B and R, which are in axial alignment with spindles 36F, L, B and R. Each spindle shaft is provided, at the end which faces casing 10, with a socket 206, adapted to fit over the squared end of its respective spindle 36 and thereby complete a driving connection between the spindle and spindle shaft.

Spindle shafts 205F and 205B are connected through gearing to map actuating means which move the map in either direction of its major or long axis and represents vehicle travel forward towards its destination or backward away from its destination. As embodied, a shaft 207 is adapted to be driven in one direction by spindle shaft 205F through bevel gears 208 and in the opposite direction by spindle shaft 205B through bevel gears 209. To the top of shaft 207 is secured a bevel gear 210 which meshes with a bevel gear 211 fixed on a cross shaft 212 which is journaled at its ends in the upwardly extended sides 213, 214 of bracket 200. A pair of friction rollers 215 are secured to the cross shaft 212 adjacent the bracket sides 213, 214, and when rotated, serve to move the map 216 in one direction or the other. The rollers 215 engage the margins of map 216 on its under side and directly above the point of contact are a pair of pressure rollers 217 mounted upon a free shaft 218 which is journaled in slide blocks 219 that slide in guideways 220 formed in bracket sides 213, 214. Thumb screws 221 above each block 219 permit adjustment of the pressure between rollers 217 and rollers 215 whereby the map is held securely therebetween and moved by roller rotation without danger of slippage.

The map 216 consists of a strip, the major axis of which is considerably longer than its minor axis or width. The scale is such that it will incorporate the distance from starting point to destination and any deviation to the right or left of the course planned.

To conserve space means may be provided for carrying the map as a pair of scrolls and exposing only a small area to view and to the course tracing means. As embodied, a forward scroll bar 225 is journaled in bracket sides 213, 214, and provided with a slot 226 in which one end of the map may be secured. From scroll bar 225 the map is passed over a guide roller 227, a guide plate 228, between drive and pressure rollers 215, 217, over a guide table 229, another guide roller 230 to rear scroll bar 231 slotted to receive the leading end of the map.

Means are provided for winding the map upon whichever scroll bar is appropriate to the direction in which the map may be moving and to insure that the opposite scroll bar is free to pay out accordingly. As embodied, the forward scroll bar 225 projects outside of bracket wall 214 and is provided with a small pulley 232 which may be driven by a coiled-spring belt 233 from a larger pulley 234 mounted upon the projecting end of cross shaft 212. Pulley 234 is driven in one direction only by shaft 212 by means of a conventional ball clutch 234' mounted within the pulley hub. The direction of drive is such that when the map is moved towards the scroll bar 225 the bar is caused to roll up the map. The ratio between pulleys 232 and 234 is such that the scroll bar pulley 232 tends to rotate more than the amount necessary to roll up the map regardless of the diameter of the scroll bar, but, since the map movement is under complete control of the drive and pressure rollers 218, 217, the tendency to excess rotation is absorbed in the slipping of belt 233.

Similar mechanism is provided for in connection with the rear scroll bar 231, a small pulley 235 being fixed on the end of the bar and driven through a spring belt 236 from a large pulley 237 mounted on cross shaft 212 adjacent to pulley 234. The hub of pulley 237 is provided with a ball clutch 238 similar to that in pulley 234 but adapted to being driven in the opposite direction by shaft 212. Thus, whichever scroll bar is being driven to wind up the map, moved in its direction, the other scroll bar is free to pay out the map the necessary amount.

To produce the line on the map 216 to represent the vehicle course, a stylus 240 may be provided which is adapted to make a mark on the map surface as by ink or otherwise. The stylus 240 is spring mounted upon a block 241 slidably mounted upon a pair of guide rods 242 which are secured in the bracket sides 213, 214. A thumb screw 243, threaded into block 241, serves to provide adjustment of the contact pressure between the stylus 240 and the surface of the map 216. Journaled in the bracket sides and positioned between the guide rods 242 is a screw member 243 which passes through a threaded aperture in the stylus block 241 and moves the latter to the right or left as the screw 243 is rotated in the appropriate direction. The stylus is thereby caused to trace a line parallel to the width of the map and represents a vehicle course, if the map is stationary, 90° to the right or left of the course, as the case may be.

Spindle shafts 205L and 205R are connected through gearing to the stylus screw 243, the shaft 205L being adapted to rotate the screw so as to move the stylus to the left of the course and shaft 205R being adapted to rotate the screw so as to move the stylus to the right of the course. As embodied, a shaft 244 is adapted to be driven in one direction by spindle shaft 205L through bevel gears 245 and in the opposite direction by spindle shaft 205R through bevel gears 246. On one end of shaft 244, outside of bracket 206, is fixed a bevel gear 247 which meshes with gear 248 on the end of a vertical shaft 249. Shaft 248 rotates the stylus screw 243 by its connection thereto through bevel gears 250.

To facilitate the loading of the map 216 upon the scroll bars 225 and 231 and to adjust the position of it in respect to the stylus 240, small hand wheels 251 and 252 are fixed upon the ends of the respective bars external to the bracket side 213. Adjustment of the stylus 240 in respect to the

map 216 is accomplished by manipulation of a hand wheel 253 fixed upon the end of stylus screw 243.

From the foregoing description it will be understood that a novel and useful mechanism is provided for mechanically converting the travel and steering movements of a vehicle into a self-orienting map-following and recording instrument regardless of the direction and speed of movement of the vehicle. In addition the compass direction of the vehicle is continuously indicated by the means of the mechanism shown in Figs. 1, 2 and 4 so that the instrument may be utilized as a mechanical compass for the guidance of the operator of the vehicle, said compass being purely mechanical in its operation and thus depending neither upon the usual magnetic needle effect nor upon any gyroscopic effect for its operation and accuracy. The invention therefore provides a mechanical compass or direction indicator in addition to its other features.

It will be understood that the mechanism shown in Fig. 1 is in itself a complete mechanical unit which is applicable to any of the uses previously referred to, merely depending upon the prime movers applied to the shafts 20 and 116. On the other hand, the same basic mechanism may be caused to operate in reverse by applying prime movers to the four shafts 36 R, L, F and B, whereby the reverse operation (in the mathematical sense) will be performed and the results thereof obtained from the shafts 116 and 20.

The invention in its broader aspects is not limited to the specific mechanisms shown and described but departures may be made therefrom within the scope of the accompanying claims without departing from the principles of the invention and without sacrificing its chief advantages.

What I claim is:

40. 1. A mechanism of the class described including in combination a prime mover for imparting movement corresponding to the length of a vector, four members capable of being driven by said prime mover, means for connecting and disconnecting said members independently of each other with said prime mover to be driven thereby, a device positionable according to the quadrant angle of the vector in any quadrant thereof, said device having control instrumentalities movable proportionately to the sine of such quadrant angle for controlling said connecting and disconnecting means to connect selected ones of said four members to the prime mover for periods proportional to the sine of such angle, said control instrumentalities also being movable proportionately to the cosine of said angle for controlling said means to connect other of said members to the prime mover for periods proportional to said cosine.
45. 2. A mechanism of the class described including in combination a prime mover for imparting movement corresponding to the length of a vector, four members capable of being driven by said prime mover, electromagnetic clutch means for connecting and disconnecting said members independently of each other with said prime mover to be driven thereby, a device positionable according to the quadrant angle of the vector in any quadrant thereof, said device having control instrumentalities movable proportionately to the sine of such quadrant angle for controlling said electromagnetic clutch means to connect selected ones of said members to the prime mover for periods proportional to the sine of such angle, said control instrumentalities also being movable
- 50.
- 55.
- 60.
- 65.
- 70.
- 75.

proportionately to the cosine of said angle for controlling said clutch means to connect other of said members to the prime mover for periods proportional to said cosine.

3. In a device of the class described, in combination, a member positionable according to the direction of travel of a vehicle and means for so positioning said member comprising a device moved by the vehicle steering control through an angle equal to the angle of steering, a member driven proportionally to the travel of the vehicle, and means for transmitting turning motion from said driven member to said directional member proportionally to the sharpness of the steering angle during the period of time that the vehicle is turning at said steering angle, four members capable of being driven by said driven member, means for connecting and disconnecting said members independently of each other with said driven member to be driven thereby, said member positionable according to the direction of travel having control instrumentalities movable proportionately to the sine of such steering angle for controlling said connecting and disconnecting means to connect a selected one of said four members to the prime mover for periods proportional to the sine of such angle said instrumentalities also being movable proportionately to the cosine of said angle for similarly controlling the connecting of another one of said members to the driven member for periods proportional to said cosine.

4. A mechanism of the class described includ-

ing in combination a prime mover for imparting movement corresponding to the length of a vector, four members capable of being driven by said prime mover, means for connecting and disconnecting said members independently of each other with said prime mover to be driven thereby, a device positionable according to the quadrant angle of said vector, said device having control instrumentalities responding to the sine and cosine respectively of said angle, said instrumentalities being designed to control said connecting and disconnecting means so as to impart driving movements to said four members from the prime mover in proportion to the respective 10 rectangular components of the vector angle in any quadrant thereof.

5. A mechanism of the class described including in combination a prime mover for imparting movement corresponding to the length of a vector, four members capable of being driven by said prime mover, means for connecting and disconnecting said members independently of each other with said prime mover to be driven thereby, a resolving device positionable according to the angle of the vector in any quadrant thereof, said device having control instrumentalities movable proportionately to the sine of said angle, said instrumentalities being designed to control said connecting and disconnecting means so as to 20 impart driving movements to any one of said four members for periods proportional to the sine of said quadrant angle.

WILLARD E. OLIPHANT.
